UNITED STATES PATENT OFFICE.

WILLIAM CAREY PORTER, OF McCALL CREEK, MISSISSIPPI.

DESIGN FOR AN AWL.

47,893.

Specification for Design. Patented Sept. 28, 1915.

Application filed June 12, 1915. Serial No. 33,805. Term of patent 14 years.

To all whom it may concern:

Be it known that I, WILLIAM CAREY PORTER, a citizen of the United States, residing at McCall Creek, in the county of Franklin and State of Mississippi, have invented a new, original, and ornamental Design for Awls, of which the following is a specification, reference being had to the accompanying drawing, forming a part thereof.

The figure is a perspective view of an awl, showing my new design.

I claim:

The ornamental design for an awl, as shown.

WILLIAM CAREY PORTER.

Witnesses:

B. L. POLK,
T. J. WALKER.
